SURGE ARRESTER

Charles Adin Fox, St. Louis, Mo., assignor to
 James R. Kearney Corporation, St. Louis, Mo.,
 a corporation of Missouri

Application January 21, 1938, Serial No. 186,059

3 Claims. (Cl. 175—30)

This invention relates generally to surge arresters of the type provided with a drainage gap disposed between spaced electrodes, one of which is connected to the line to be protected and the other to a suitable ground, which drainage gap is enclosed by a dielectric structure capable of evolving a substantially non-ionized gas when subjected to the heat of an arc discharge which tends to extinguish the arc, the predominant object 5 of the invention being to provide an improved surge arrester of the type mentioned which because of its improved details of construction and arrangement is capable of performing its intended function in a highly efficient manner.

10 Fig. 1 is a sectional view of the improved surge arrester illustrating same as it appears when mounted for use.

15 Fig. 2 is an end elevation of the improved surge arrester looking toward the open end of the device.

Fig. 3 is a cross-section on the line 3—3 of Fig. 1 looking in the direction of the arrow.

In the drawing, wherein is shown for the purpose of illustration, merely, one embodiment of the invention, A designates the improved surge arrester generally. The surge arrester A comprises a main housing 1 which is of tubular formation, having an opening formed longitudinally therethrough which is of relatively small diameter 25 throughout the greater portion of the length of the housing as indicated at 2 and being of substantially increased diameter at the open end of the housing as indicated at 3, there being an annular shoulder 4 at the junction of the portions of the opening which are of smaller and larger diameters. The opening portion 2 extends from its point of junction with the larger opening portion 3 to the opposite or closed end of the main housing 1, and at said closed end of the main housing 40 an annular depression 5 is formed in the wall thereof which serves a purpose to be hereinafter set forth. The main housing 1 of the improved structure is formed of porcelain or other suitable electrical insulating material, and if desired said housing may be provided with annular external ribs 1a and grooves 1b as desired.

Attached to the main housing 1 at the closed end thereof is a head 6 which is formed of metal or other electrical conducting material. The head 6 is of the approximate diameter of the main housing 1 and it is provided with prong-like teeth 7 which extend into the depression 5, said teeth being arranged in an annular row as shown in Fig. 3 and each adjacent pair of teeth 55 of the annular row of teeth being so bent that

said adjacent teeth are disposed in divergent relation with respect to each other as shown in Figs. 1 and 3. In order to secure the head 6 to the main housing 1 the annular depression 5 is filled with a suitable cement which is adapted to harden, the divergent teeth being embedded in the cement so as to form keys which aid in securely attaching the head 6 to the main body portion. The head 6 is provided with a centrally located, integral collar portion 6' and said head 10 gradually increases in thickness from the circumferential edge thereof to the location of said collar portion. Also the head is provided with a centrally disposed screwthreaded opening 7' formed therethrough which is partly located in 15 the collar portion thereof.

Screwed into the screwthreaded opening 7' of the head 6 is the screwthreaded end portion 8' of a sleeve 8, said sleeve portion being provided with external screwthreads which engage the screw- 20 threads of the opening 7' formed in the head 6, and internal screwthreads which serve a purpose to be hereinafter set forth. When the sleeve is arranged in its fully screwed-in position with respect to the head 6 an annular shoulder 8a formed 25 on said sleeve engages the outer end face of the collar portion of said head. At its outer end portion the sleeve 8 supports an operating element 9 formed of porcelain or other suitable electrical insulating material, said operating element being 30 provided with an opening 10 into which the outer end portion of the sleeve is extended.

The opening 10 of the operating element is of slightly greater diameter than the sleeve so that an annular space 11 is present between the 35 wall of said opening 10 and the outer surface of the sleeve, and this space is of increased width at an end thereof, as indicated at 12, due to the fact that the opening 10 at this point is of increased diameter. Additionally the wall of the 40 opening 10 of the operating element and the surface of the sleeve 8 are provided with annular depressions 13 which open toward each other into the annular space 11. In order to secure the operating element 9 to the sleeve 8 cement is 45 introduced into the annular space portions 11 and 12 and into the depression 13, said cement hardening therein to securely attach said operating element and said sleeve together. The operating element 9 includes a skirt portion 14 which overlies the head 6 so as to afford protection thereto.

Screwthreadedly disposed in the internally screwthreaded end portion of the sleeve 8 is an externally screwthreaded plug 15 in which an opening is formed longitudinally therethrough. 55

The plug 15 is located inwardly of the outer end of the screwthreaded end portion of the sleeve as shown in Fig. 1, and registering screwthreaded apertures 16 and 17 are formed in portions of the 5 plug 15 and the sleeve 8. The plug 15 supports an electrode 18 which is in the form of a rod, said electrode being extended through the opening formed through the plug. The electrode is secured in place with respect to the plug 15 by 10 a set screw 19 which is screwthreadedly disposed in the alined apertures 16 and 17 formed in portions of the plug and sleeve respectively, said set screw being screwed into gripping contact with the electrode so as to fix same in position and said 15 set screw serving also to prevent unintended rotation of the plug with respect to the sleeve. The set screw is preferably provided with a noncircular opening 19' which is adapted to receive a suitable tool employed for rotating the set screw.

20 Supported by the sleeve 8 and extended longitudinally within the opening portion 2 formed in the main housing 1 of the structure A is a tube structure 20 which comprises an outer tubular element 20a formed of Bakelite or other suitable 25 material and an inner tubular element 20b formed of horn fiber or equivalent material characterized by the ability to give off a substantially non-ionized gas when subjected to the heat of an arc discharge. The tubular elements 20a and 20b 30 are combined in the form of a unitary structure and the outer tubular element is externally screwthreaded at its opposite ends as indicated at 20c, one screwthreaded end portion of the tube structure being screwed in the outer portion of the 35 screwthreaded part of the opening through the sleeve 8. The end of the tube structure 20 opposite to the end thereof which is screwed in the screwthreaded portion of the opening of the sleeve 8, is spaced longitudinally of the opening portion 2 of the 40 main housing 1 from the location of the annular shoulder 4 within said main housing as indicated at 21 in Fig. 1, and the end of electrode 18 which is located within the tubular structure 20 is spaced longitudinally of said tubular structure 45 from the end thereof which is disposed in spaced relation with respect to the location of the shoulder 4 of the main housing.

Located within the enlarged opening portion 3 of the main housing 1 is a second electrode 22 50 which is in the form of a ring, an opening formed through said electrode which comprises an opening portion 22a of relatively small diameter at one side of the electrode, a flared intermediate portion 22b, and an opening portion 22c at the 55 opposite side of the electrode which is of increased diameter. The electrode 22 is arranged in contact with the annular shoulder 4 within the main housing 1, said electrode being of such diameter that an annular space is present between the circumferential face of the electrode 60 and the wall of the opening portion 3 of the main housing. The electrode 22 is secured in place within the opening portion 3 by means of suitable cement 23 which is arranged in the annular space 65 mentioned above, the wall of said opening portion 3 and the circumferential face of the electrode being provided with annular grooves 24 in which portions of the body of cement are disposed to provide keys which aid in securely fixing 70 the electrode in place.

The electrode 22 has formed therethrough an opening 25 which is disposed in alinement with oppositely disposed openings 26 formed in opposed portions of the wall of the main housing 75 which surround the opening portion 3 thereof.

These alined openings receive an end portion of a conductor Ca which provides an electrical connection between the line to be protected and the electrode 22. As shown in Figs. 1 and 2 the conductor Ca is secured to the electrode 22 by means of set screws 28 which extend through screwthreaded openings formed in portions of the electrode and frictionally engage said conductor.

The surge arrester A is suitably supported for use, for instance by a cross arm B which has attached to it by means of a U-bolt 27 a suitable bracket 28. The bracket 28 is provided with a clamping portion 29 which embraces the circumferential edge of the head 6 and an adjacent portion of the main housing 1, said clamping portion of the bracket being provided with spaced ears 29' that are drawn toward each other by a bolt 30 so as to cause the clamping portion to clampingly engage the portions of the surge arrester which are embraced thereby. The bracket 20 29 has attached to it by means of suitable connecting means 31 a conductor Cb which leads from said bracket to a suitable ground.

In the use of the improved surge arrester what amounts to a double gap is provided, one of such 25 being an air gap defined by the space 21 between the electrode 22 and the adjacent end of the tube structure 20, and the other gap being located within the outer end portion of the tube structure between the end of the electrode 18 and the adjacent end of said tube structure. When excess voltage, caused by lightning or switching surges, flashes over between the electrodes 22 and 18 such excess voltage is by-passed to ground by way of the electrical path provided by the electrode 18, 35 plug 15, sleeve 8, head 6, bracket 28, connecting means 31 and conductor Cb. A discharge of excessive voltage across a gap in surge arresters is usually followed by a power current arc and in the use of the improved surge arrester disclosed 40 herein such arc is extinguished in the gap within the tube structure 20 and between the end of the electrode 18 and the adjacent end of the tube structure, such extinguishment of the arc resulting from the fact that substantially non-ionized 45 gas is evolved when the material of the inner tubular element 20b of the tube structure is subjected to the heat of the arc, which non-ionized gas acts to extinguish the arc.

With reference to the construction of the improved surge arrester it is to be noted that the sleeve 8, operating element 9, plug 15, electrode 18 and tube structure 20 provide a removable unit which is screwthreadedly associated with the remainder of the surge arrester by engagement of the screwthreads of the sleeve engaging the screwthreads within the opening of the head 6. Therefore the unit referred to may be unscrewed and removed from the remainder of the device 60 when it is desired to inspect the tube structure 20 or make repairs thereon. It is to be noted also that the electrode 18 may be adjusted longitudinally of its axis by unscrewing the set screw 19 to permit movement of the electrode and thereafter resetting the set screw to engage the electrode and retain it in the position to which it has been adjusted. Furthermore the tube structure 20 is externally screwthreaded at its opposite ends, hence if one end portion of the inner tubular element 20b of the tube structure becomes 70 burned or otherwise damaged in use, said tube structure may be reversed to position an unburned portion of the tube structure adjacent to the end of the electrode 18.

I claim:

1. A surge arrester comprising a unit including an elongated insulating housing open at an end thereof, an electrode located within said housing, 5 and a head fixed to said housing and forming a permanent part thereof, and a second unit removably associated with the first-mentioned unit, said second unit including a member which removably engages said head, a second electrode supported by said member and extended longitudinally within said housing with an end of said second electrode being spaced from the first-mentioned electrode to provide a gap which is located entirely within said housing, and a tubular element 10 formed of gas-evolving material which is supported by said member and embraces said second electrode and extends beyond the end of said second electrode which is spaced from the first-mentioned electrode to provide said gap, a part 15 of said gap between said first-mentioned electrode and said second electrode being located within the portion of the tubular element which extends beyond the end of the second electrode and another portion of said gap being in the form 20 of an air gap.
2. A surge arrester comprising a unit including an elongated insulating housing open at an end thereof, an electrode of tubular formation located within said housing, and a head fixed to said housing and forming a permanent part thereof, and a second unit removably associated with the first-mentioned unit, said second unit including a member which removably engages said head, a second electrode supported by said member and 25 extended longitudinally within said housing with an end of said second electrode being spaced from the first-mentioned electrode to provide a gap which is located entirely within said housing, a tubular element 30 formed of gas-evolving material which is supported by said tubular member and embraces said second electrode and extends beyond the end of said second electrode which is spaced from the first-mentioned electrode to provide said gap, a part 35 of said gap between said first-mentioned electrode and said second electrode being located within the portion of the tubular element which extends beyond the end of the second electrode and another portion of said gap being in the form 40 of an air gap, and an insulating operating element fixed to said tubular member.
3. A surge arrester comprising a unit including an elongated insulating housing open at an end thereof, an electrode located within said housing, and a head fixed to said housing and forming a permanent part thereof, and a second unit removably associated with the first-mentioned unit, 10 said second unit including a tubular member which is exteriorly screwthreaded to screwthreadedly engage said head and is interiorly screwthreaded, a screwthreaded plug which is screwed into the screwthreaded interior of said tubular member and is provided with an opening formed longitudinally therethrough, a second electrode 15 extended through the opening of said plug to provide for the support of said second electrode by said plug, a set screw which is arranged in 20 aligned screwthreaded openings formed in said tubular member and said plug and frictionally engages said second electrode to secure it in place with respect to said plug, said set screw serving the additional function of preventing relative 25 rotary movement of said tubular member and said plug, said second electrode being extended longitudinally within said housing with an end of the second electrode spaced from the first-mentioned electrode to provide a gap which is located entirely within said housing, a tubular element 30 formed of gas-evolving material which is supported by said tubular member and embraces said second electrode and extends beyond the end of said second electrode which is spaced from the first-mentioned electrode to provide said gap, a part 35 of said gap between said first-mentioned electrode and said second electrode being located within the portion of the tubular element which extends beyond the end of the second electrode and another portion of said gap being in the form 40 of an air gap.

CHARLES ADIN FOX. 45
